CLAIM

The ornamental design for an operator station of a card personalization system, as shown and described.

DESCRIPTION

FIG. 1 is a perspective view of an operator station according to our new design;

FIG. 2 is a front elevation view of the operator station depicted in FIG. 1;

FIG. 3 is a rear elevation view of the operator station depicted in FIG. 1;

FIG. 4 is a right side elevation view of the operator station depicted in FIG. 1;

FIG. 5 is a left side elevation view of the operator station depicted in FIG. 1;

FIG. 6 is a top plan view of the operator station depicted in FIG. 1; and,

FIG. 7 is a bottom plan view of the operator station depicted in FIG. 1.

The broken lines in the drawings are for illustrative purposes only, and the broken lines form no part of the claimed design.
